[57] CLAIM

The ornamental design for a ceiling fan, as shown and described.

DESCRIPTION

FIG. 1 is an environmental bottom-front perspective view of a ceiling fan showing my new design;

FIG. 2 is an environmental rear-bottom perspective view thereof;

FIG. 3 is an environmental left elevational side view thereof;

FIG. 4 is an environmental right elevational side view

thereof; and,

FIG. 5 is an environmental rear-top perspective view.

The broken line showing of the support in FIGS. 1-5 and the chain in FIGS. 1, 2, and 5 is for illustrative purposes only

and forms no part of the claimed design.
